UNITED STATES PATENT OFFICE.

HENRY P. CLAUSEN, OF CHICAGO, ILLINOIS, ASSIGNOR TO AMERICAN ELECTRIC TELEPHONE COMPANY, A CORPORATION OF NEW JERSEY.

TELEPHONE-TRANSMITTER.

SPECIFICATION forming part of Letters Patent No. 787,610, dated April 18, 1905.

Application filed August 19, 1901. Serial No. 72,623.

To all whom it may concern:

Be it known that I, HENRY P. CLAUSEN, a citizen of the United States of America, and a resident of Chicago, Cook county, Illinois, have invented a certain new and useful Improvement in Telephone - Transmitters, of which the following is a specification.

My invention relates to certain improvements in telephone-transmitters of the type ordinarily known as a "microphone."

In a telephone-transmitter a thin circular disk of suitable material, preferably of carbon or some metal, called the "diaphragm," is held in a suitable case in proximity to a mouthpiece, so that the articulated sound-waves are concentrated upon the diaphragm which is held at its edges, and thus vibrate the diaphragm. It is necessary to provide a conducting material which shall be influenced by the vibrations of the diaphragm to vary the intensity of an electric current. The material which has usually been employed in the modern types of transmitters for this purpose is granular carbon, which is held within a suitable receptacle. The electrodes or the members with which the circuit-wires are connected usually consist of carbon disks held apart by the mass of granular carbon interposed between them, one of said disks of carbon being connected with the diaphragm, so that the vibrations of the latter are imparted to the former, causing said electrode to approach toward and recede from the other carbon disk or electrode. By this means the mass of granular carbon is varied in its density, and as the electric current passes through the mass of carbon the resistance of the circuit varies in proportion to the variation of density of the mass of carbon granules.

In transmitters generally it is desirable to provide a self-contained piece of apparatus the parts of which are readily and conveniently adjusted and which when adjusted remain in secure and permanent relationship and also to produce a completed piece of apparatus which is small and compact. It is of further importance to provide means by which the electrode or carbon disk connected with and moved by the diaphragm shall have a

maximum amplitude of vibration, and thereby act to vary the range of density of the mass of carbon granules.

My invention is particularly designed to obtain in a transmitter of this type a maximum range of vibration or movement of the diaphragm-electrode in its relation to the relatively fixed back electrode. To do this, I provide a shell formed of two parts joined and held together, which when assembled provides an annular receptacle having springy or resilient supplemental diaphragm or walls and an intermediate annular body of material which, presenting its cross-section to the line of stress, is inflexible. The diaphragm-electrode or disk of carbon is mounted upon one flexible springy wall of the receptacle, and the back electrode is mounted upon the other flexible wall of said receptacle, the mass of granular carbon being disposed within said receptacle and between said carbon electrodes. The diaphragm is secured to one wall of the receptacle, and the center of the other wall of the receptacle is rigidly secured to what is known as the "supporting-bridge," which latter is connected to the casing or rim of the instrument. Thus the vibrations of the diaphragm are imparted to the springy front wall of the receptacle and to the diaphragm-electrode secured thereto; but as the other wall is only secured to the back electrode at its center it has a marginal vibration imparted to it through the annular intermediate ring of the receptacle, which permits a further and more complete approach of the diaphragm-electrode toward the back electrode. In effect, this action, as will be more particularly made apparent hereinafter, produces a complete vibration of the diaphragm-electrode by reason of the movement of the flexible walls of the receptacle, and as the front and back walls of the receptacle are of springy or resilient material they are adapted to serve as supplemental front and back vibratory diaphragms and as medium of yielding and resilient connection between the main diaphragm and the bridge. The two springy supplemental diaphragms constitute a resilient connection for yieldingly and resiliently opposing relative

movement between the two electrodes which alternately compress and release the granular carbon. A transmitter constructed on this principle is exceedingly efficient and sensitive 5 and is capable of a powerful and natural transmission of the voice tones, notwithstanding the fact that it is simple and comparatively inexpensive to manufacture.

My invention has certain other objects in 10 view relating more particularly to adjustment and compactness, which will be particularly set forth by reference to the accompanying drawings, in which—

Figure 1 is a vertical section of the complete apparatus shown assembled together. Fig. 2 is a rear view of the said apparatus with the outer casing removed. Fig. 3 is a view of the various parts non-assembled, but in their relative position to be assembled. Fig. 20 4 is an enlarged vertical section through the receptacle containing the electrodes and the mass of granular carbons.

The transmitter is contained within an ordinary case A, which is cup-shaped in form, 25 and the cover B, holding the mouthpiece D, is secured upon the cup-shaped casing in any suitable manner. The diaphragm E is held against the cover B at its rim, so that the central portion thereof is at the inner end of the 30 mouthpiece. The bridge H is bent upon the cover B, as shown at h. The parts thus described are ordinarily used in a transmitter.

The novel feature of my invention resides in the receptacle for holding the electrodes 35 and the mass of granular carbon, which I have designated as a whole at J. This receptacle J, which is illustrated more clearly in the large view, Fig. 4, is comprised of two counterpart portions, Fig. 3, which when joined 40 together provide a circular-shaped shell or receptacle having two vertical walls j and k and an intermediate annular ring l between the vertical walls. These two walls j and k are of thin metal and are consequently flexible. 45 The annular ring l, presenting a cross-section of the material, joins the two flexible walls together and, as will be seen, imparts the movement of one wall to the other. The flexible wall k is electrically connected to the diaphragm E by the contacting sleeve m, and the metal disk n is also electrically connected to the diaphragm by means of the screw-threaded stem o and nut secured upon said stem. 50

The diaphragm-electrode K, consisting of 55 a carbon disk, is secured upon the metal disk n in any suitable manner. A sleeve p is rigidly held in the bridge H by means to be described, and the stem q extends within said sleeve p, these parts being isolated by the insulating-sleeve r. A disk s is secured upon the inner end of the stem q, and the back electrode of carbon L, consisting of a disk of copper, is mounted upon the metal disk s. A mass of granular carbon M is disposed with- 60 65 in the receptacle J between the diaphragm-

electrode K and the back electrode L. The stem q and disk s, carrying the back electrode L, are securely held in position by means of the nut t upon the outer end of the stem q, said nut t being insulated from the sleeve p. 70

I provide a gripping-yoke of counterpart members N and O, Fig. 2, which are bolted together and encircling the sleeve p to hold the same securely and rigidly in position upon the yoke. 75

The stem q, bearing the disk s, which carries the back electrode L, is connected by a wire P with a conducting-stem Q, which latter is connected with one of the circuit-leads. The other one of the circuit-leads may be connected 80 at any suitable point to the casing A.

The operation of my device is as follows: When the diaphragm E is vibrated by the impact of the sound-waves, its movement of vibration is transmitted to the flexible wall k at 85 the point of connection between the said wall and the sleeve m and stem o. Assume the movement of the diaphragm to be inward, the disk n is also moved inward within the receptacle J by its connection to the stem o, thus 90 causing the diaphragm-electrode K to have an inward movement to compress the mass of granular carbon M between its surface and the surface of the back electrode L, which is held in a stationary position by the disk s and the stem q held rigidly in the yoke H. As stated, the flexible wall k yields and upon its inner thrust dishes at its center, and this movement of the flexible wall k is communicated to the opposite flexible wall j by means 95 of the intermediate annular ring l, the wall j thus dishing its outer edge as it is held at the center rigidly by means of the sleeve p. This yielding of the two walls k and j permits the diaphragm-electrode K to obtain a wide range 100 of movement in order to compress or release the mass of granular carbon, and when the diaphragm by its opposite or outward movement releases the inward pressure upon said walls they return to their normal position, 105 the wall j being stopped and held from false vibration by means of the engagement with the disk s and flexible wall j.

In use the forward thrust of the diaphragm E will tend to dish the forward wall k, and this forward thrust will then be communicated through the insulating-ring l and the peripheral portions of the casing to the back wall j. In this way the forward thrust of the diaphragm E operates to momentarily 110 flex the walls k and j in such manner as to cause them to become concave on their outer surfaces. By thus yielding to the inward or forward thrust of the diaphragm E the back wall j permits the carbon disk or electrode K to approach much closer to the carbon disk or electrode L. In this way the vibratory movement or shift on the part of the electrode K is increased to quite an extent, and by so doing an increased agitation of the granular 115 120 125 130

carbon is of course also secured. As stated, the flexing or yielding of the back wall *j* results in a momentary dishing of this wall and also the forward wall *k*, each wall being momentarily rendered concave on its outer surface. It will be observed, however, that an outward or reverse movement on the part of the diaphragm *E* will not cause the walls *k* and *j* to flex in an opposite direction—that is to say, in such manner as to become convex on their outer surfaces. This is due to the fact that these walls *k* and *j* are held against bulging or becoming outwardly convex by having their inner surfaces arranged to bear 15 against the flat outer surfaces of the plates *n* and *s*. This will be readily understood by referring to Fig. 4, in which it will be seen that the central portion of plate *k* is clamped tightly between the sleeve *m* and the plate *n* 20 and that in a similar way the central portion of plate *j* is clamped tightly between plate *s* and the sleeve *p*. In this way the walls *k* and *j* are made capable of flexing or dishing in such manner as to render their outer surfaces 25 concave, but never in such manner as to cause their outer surfaces to bulge or become convex. In this way the granular carbon and the carbon electrodes are inclosed in a flexible casing, which is preferably sealed by 30 the ring *l*. The yielding character of the back wall of the carbon casing thus provided insures a greater and more natural vibration on the part of the diaphragm *E* and carbon electrode *K*, thereby insuring the desired increase of agitation on the part of the granular 35 carbon.

While the peripheral portions of the sheet-metal casing are, as stated, non-flexible and unyielding, the front and back walls are of a 40 springy or resilient nature, and therefore yield to the forward thrust of the diaphragm. Being composed of springy or resilient sheet-metal walls, the casing which thus incloses the carbon electrodes and granular carbon is 45 capable of restoring itself to a normal condition—that is to say, of restoring the two electrodes to their normal relative positions when the diaphragm ceases to vibrate. In other words, these two resilient or springy front 50 and back walls of the carbon box or casing serve as supplemental diaphragms, which vibrate with the main or acoustic diaphragm *E*. The metal sleeve held by the bridge *H* serves as a backing for opposing the forward thrust 55 of the diaphragm, and it is between the back electrode and the end of this backing that the middle portion of the back flexible or springy wall of the sheet-metal casing is clamped or held. In this way the central portion of the 60 flexible back wall *j* is held against movement, and with the relative proportions of the back electrode and the sleeve *p* the outer or peripheral portions of this back wall are prevented from moving forward of their normal 65 position. In other words, the marginal or

outer portions of this back wall *j* are arranged to yield to the pressure of the diaphragm and move back to some extent, but are prevented by the back electrode from moving in an opposite direction. Thus the back flexible or 70 springy wall of the carbon-box is permitted to dish or become outwardly concave, but never becomes outwardly convex. The front wall *k* is, however, so mounted and held as to be capable of becoming either concave or convex on its outer surface. This is due to the fact that the front electrode is provided with a reduced hub portion *k'*, against which the said front wall is clamped by the sleeve *m*. This 75 construction provides a slight space between the plate *n* of the front electrode and the inner surface of the said flexible front wall. In this way when the diaphragm moves forward this front wall becomes dished or concave on its outer surface, and when the diaphragm reacts or draws back the said wall may then become more or less convex on its outer surface. Furthermore, it will be seen that with this arrangement the front flexible wall has 80 both a bodily and a flexing or vibrating movement. While the middle portion of the back wall is held against movement, the middle portion of the front wall is permitted to move with the diaphragm, and owing to the flexibility of the back wall the said front wall 85 also has a slight bodily movement in addition to its flexing or bending. While the ring *l* and the plate or disk *j'* serve to insulate the back electrode from the sheet-metal casing, the arrangement is such that the front electrode 90 and said casing are electrically connected. With this arrangement the electrical circuit includes the terminal or contact *Q*, the wire *P*, the stem *q* of the back electrode, the disk or plate *S*, and the carbon plate *L* of the 95 back electrode, the granular carbon *M*, the carbon disk *K*, the metal plate *n* of the front electrode, the hub portion *k'* of the front electrode, the flexible or sheet-metal casing which incloses the electrodes and carbon, the metal 100 sleeve *p*, the bridge *H*, the casing *A*, and the boss *a* on the said casing, the latter serving as the other contact or terminal. In this way 105 it will be seen that the current does not traverse the diaphragm and that the arrangement obviates the necessity of employing certain objectionable connecting devices heretofore employed in transmitters of this character. As stated, the current flows through 110 the transmitter-casing and the electrodes and back to the terminal or contact *Q*, the resilient or springy sheet-metal casing which incloses the carbon serving as medium of electrical connection between the front electrode and the bridge *H*. As explained, the sheet-metal casing or box for inclosing the carbons is preferably made in two sections, each of 115 which is preferably provided with a flange. The two flanges can be united by the clamp-ring *l*, and the character of the closure 120

125 130

can be such as to hermetically seal the casing and inclose the carbon. Solder of course can be employed, if desired, to effect the closure and to permanently seal and connect the two sections of the casing.

As illustrated, it will be seen that the metallic sleeve, the metal box or receptacle J, the vibratory or front electrode, the granular carbon, the stationary back electrode, and the metal stem, *g*, are all connected up in series in the order mentioned, the said box or receptacle constituting medium of electrical connection for the flow of current between the said sleeve and stem. This arrangement obviates the necessity of including the main diaphragm in the electrical circuit.

The two resilient auxiliary diaphragms *k* and *j* yield readily and permit the desired extent or amplitude of relative vibration between the two electrodes, and at the same time it will be seen that the character of these two resilient auxiliary diaphragms is such as to enable the main diaphragm to give the box or receptacle a bodily vibratory movement, but of somewhat less amplitude than the vibratory movement of the front electrode, and thus there is relative movement between the front electrode and the peripheral portions of the box, between the back electrode and the peripheral portions of the box, a slight bodily vibration on the part of the box, and consequently a relative movement of the peripheral portions of the box first toward and then away from the main diaphragm. Thus constructed the transmitter is of an exceedingly satisfactory and efficient character and well calculated to insure improved transmission.

It will be seen that one of the novel features of my invention consists of two thin resilient walls, each provided with an electrode and rigidly supported at their outer edges, together with granular carbon or other equivalent material interposed between the two electrodes, and as to the three elements—to wit, one electrode, another electrode, and means for rigidly supporting the said walls at their outer edges—at least one of said three elements being held stationary, whereby the granular carbon is subjected to variable pressure when the two walls are flexed or vibrated, together with main diaphragm means adapted to receive the voice-vibrations and connected to alternately compress the centers of said auxiliary diaphragms toward each other and draw the same apart and to thereby produce the relative movement between the two opposed electrodes.

What I claim as my invention is as follows:

1. In a telephone-transmitter, the combination with the diaphragm and mountings thereof, of a carbon-holding receptacle comprising flexible springing walls and an intermediate inflexible rim, a carbon disk comprising one

of the electrodes within said receptacle rigidly connected with the diaphragm, one of the said walls being also connected with said diaphragm, and yielding under the influence thereof, another disk of carbon within said receptacle constituting the back electrode, also connected with the other flexible wall which likewise yields under the influence of the diaphragm, said back electrode being stationary, and granular carbon intermediate between said electrodes, whereby the said walls move with the movement of the diaphragm.

2. A telephone-transmitter comprising a diaphragm, front and back electrodes, the front electrode being connected by a stem with the said diaphragm, granular carbon between said electrodes, a sheet-metal box or casing inclosing said electrodes and granular carbon, said box or casing being provided with springy or resilient front and back walls which yield and permit the front electrode to approach the back electrode, and a backing for holding the back electrode and the middle portion of the said springy or resilient back wall against movement.

3. A telephone-transmitter comprising a diaphragm, a front electrode connected to vibrate with said diaphragm, a back electrode held by a stationary backing, granular carbon between said electrodes, the said front electrode being provided on its back with a hub or raised portion, a box or casing inclosing said electrodes and granular carbon, said box or casing being provided with relatively thin springy or resilient front and back walls, a nut and sleeve for clamping the said front wall against the said hub or raised portion on the front electrode, the said front wall thereby being permitted to flex or bend in either direction, a nut and sleeve for clamping the middle portion of the said back wall against the flat back or outer surface of the said back electrode, the said back wall thereby being permitted to flex or bend in one direction only, and the two resilient or springy walls thus held being adapted to yield to the thrust of the diaphragm and permit the front electrode to approach the back electrode.

4. A telephone-transmitter comprising a diaphragm, a backing, a springy or resilient sheet-metal box or casing serving as a yielding connection between said diaphragm and said backing, front and back electrodes and granular carbon inclosed by said box or casing, suitable insulation for insulating the said box or casing from the said back electrode, said front electrode being electrically connected with said box or casing, a suitable transmitter casing or body structure, electrical connection between said casing or body structure and said springy or resilient box or casing, the said transmitter casing or body structure thereby serving as one terminal of the electrical circuit, and a terminal or con-

tact piece electrically connected with the back electrode and insulated from said transmitter casing or body structure.

5. A telephone-transmitter comprising a suitable body structure, a diaphragm, a relatively large front electrode connected to vibrate with said diaphragm, a relatively small back electrode, the said front electrode having its middle portion provided with a hub or 10 raised portion, a sheet-metal casing having springy or resilient front and back walls, a nut and sleeve for clamping the front wall against the said hub or raised portion on the front electrode, granular carbon between the 15 two electrodes and inclosed by said box or casing, a sleeve of less diameter than the back electrode having its end portion adapted to clamp the middle portion of the said back wall against the back electrode, insulation between 20 said sleeve and said back electrode, a bridge having a middle portion adapted to clamp upon the said sleeve, so as to hold the back electrode against movement, an insulated terminal with which the said back electrode is 25 electrically connected, and the said body structure serving as the other terminal and being electrically connected through the medium of the said sheet-metal box or casing with the front electrode.

30. 6. A telephone-transmitter comprising a suitable body structure, a diaphragm and front electrode connected to vibrate together, a back electrode of less diameter than the front electrode, a stem extending from the back of said 35 back electrode, a stem and a hub or raised portion projecting from the outer surface of the front electrode, a sheet-metal box or casing inclosing said electrodes, granular carbon between said electrodes, a nut and a sleeve applied to the stem on the front electrode, so as 40 to clamp the front wall of said box or casing against said hub or raised portion on the front electrode, a metal sleeve insulated from the stem on the back electrode, a nut applied to 45 the stem on the back electrode and adapted to clamp said insulated sleeve and the middle portion of the back wall of said box or casing against the said back electrode, an insulating-ring for insulating the granular carbon from 50 the said box or casing, a layer of insulation between the back electrode and said box or casing, a bridge or clamping piece adapted to clamp upon the sleeve or the stem of the back electrode, so as to hold the back electrode 55 against movement, the said bridge and the box or casing serving as medium of electrical connection between the front electrode and the body structure, and an insulated terminal or contact piece having electrical connection 60 with the stem of the back electrode.

7. In a telephone-transmitter, the combination of a suitable diaphragm, oppositely-arranged electrodes, one of said electrodes being connected to vibrate with said diaphragm, a 65 springy or resilient sheet-metal casing com-

posed of two sheet-metal cups having joined marginal portions and adapted to inclose said electrodes, granular carbon between said electrodes, and a backing for holding one of said electrodes and a portion of said springy or resilient sheet-metal casing against movement. 70

8. In a telephone-transmitter, the combination of a diaphragm, a front electrode having suitable connection with said diaphragm, a stationary back electrode, granular carbon between said electrodes, and a springy or resilient sheet-metal casing inclosing said carbon and electrodes, said casing being composed of two cup-shaped parts having joined perimeters. 75

9. In a telephone-transmitter, the combination of a suitable diaphragm, a front electrode connected to vibrate with said diaphragm, a stationary back electrode, granular carbon between said electrodes, a springy or resilient sheet-metal casing composed of two sections 80 and arranged to inclose said carbon and electrodes, each section of the sheet-metal casing being provided with a flange, and a clamping-ring applied to said flanges and adapted to 85 join the two sections of said box or casing. 90

10. In a telephone-transmitter, the combination of a diaphragm, front and back electrodes, granular carbon between said electrodes, mechanical connection between the front electrode and the diaphragm, a stationary backing for said back electrode, a springy or resilient sheet-metal casing serving as electrical connection between said front electrode and said backing, said casing being composed 95 of two cup-shaped parts having their perimeters joined and inclosing said granular carbon and said electrodes. 100

11. In a telephone-transmitter, the combination of a suitable diaphragm, relatively 105 movable electrodes, granular carbon interposed between said electrodes, suitable connection whereby the vibration of the diaphragm causes relative movement between said electrodes, a springy wall between said electrodes 110 and said diaphragm, a springy wall on the other side of said electrodes, a non-yielding connection between said walls, and a member for preventing movement on the part of the middle portion of said last-mentioned wall, 115 the springy character of the two walls permitting the vibrations of the diaphragm to cause the desired relative movement between the two electrodes. 120

12. In a telephone-transmitter, the combination of a main diaphragm, front and back supplemental springy diaphragms suitably connected with said main diaphragm, front and back electrode-surfaces, granular carbon interposed between and resting in contact with 125 said electrode-surfaces, and a stationary backing connected with the central portion of the said back supplemental diaphragm and adapted to prevent vibrations of the central portion of the said back supplemental diaphragm, the 130

front and back electrode-surfaces being vibratory relatively to each other.

13. In a telephone-transmitter, the combination with a suitable diaphragm, of a chamber yieldingly mounted thereon, an electrode in said chamber and moving therewith, the electrode having a greater extent of movement than the chamber, an independently and adjustably supported stationary electrode opposed to said first-mentioned electrode and having a piston-like movement relative to said chamber, and comminuted material between said electrodes, the said chamber having a springy wall constituting a part and secured 10 to the balance thereof to which springy wall the independently-supported electrode is secured.

14. In a telephone-transmitter, the combination with a suitable diaphragm, of a chamber yieldingly mounted thereon, an electrode in said chamber and moving therewith, the electrode having a greater extent of movement than the chamber, an independently and adjustably supported stationary electrode opposed to said first-mentioned electrode and having a piston-like movement relative to said chamber, and comminuted material between said electrodes, the said chamber having a springy wall constituting a part and secured 20 to the balance thereof to which springy wall the independently-supported electrode is secured.

15. In a telephone-transmitter, the combination with a suitable diaphragm, of a chamber yieldingly mounted thereon, an electrode in said chamber and moving therewith, the electrode having a greater extent of movement than the chamber, a rigidly-secured electrode opposed to said first-mentioned electrode, and having a piston-like movement relative to said chamber, and comminuted material between said electrodes, the said chamber having a springy wall constituting a part and secured 30 to the balance thereof to which springy wall the rigidly-supported electrode is secured, and means whereby relative adjustment between the said electrodes may be effected.

16. In a telephone-transmitter, the combination with a suitable diaphragm, of a chamber yieldingly mounted thereon, an electrode in said chamber and moving therewith, the electrode having a greater extent of movement than the chamber, an independently-supported stationary electrode opposed to said first-mentioned electrode and having a piston-like movement relative to said chamber, and comminuted material between said electrodes, the said chamber having a springy wall constituting a part and secured 40 to the balance thereof to which springy wall the independently-supported electrode is secured, and means whereby relative adjustment between the said electrodes may be effected.

17. In a telephone-transmitter, the combi-

nation of a diaphragm, front and back electrodes, a metallic box inclosing the said electrodes, comminuted material interposed between said electrodes, insulation between said comminuted material and the inner surface of said box, the front electrode being electrically connected with the box and the back electrode being insulated therefrom, a metallic stem secured to the back electrode, a sleeve of insulation on said stem, a metallic sleeve on said sleeve 70 of insulation, the said metallic sleeve being electrically connected with said box, and a metallic member in which said metallic sleeve is adjustably clamped.

18. In a telephone-transmitter, the combination of a diaphragm, front and back electrodes, comminuted material interposed between said electrodes, a box inclosing said electrodes and comminuted material and provided with springy front and back walls, a 80 terminal having electrical connection with said back electrode, a bridge for adjustably supporting the back electrode, another terminal, an electrical connection between said last-mentioned terminal and the front electrode 90 including said bridge and box, the comminuted material and back electrode being insulated from the box and bridge.

19. In a telephone-transmitter, the combination of a diaphragm, front and back electrodes, the front electrode being connected with said diaphragm, a bridge for adjustably supporting the stationary back electrode, comminuted material interposed between said electrodes, and a box inclosing said electrodes 95 and comminuted material, said box having flexible and springy front and back walls serving as medium of yielding connection between the said diaphragm and bridge.

20. In a telephone-transmitter, the combination of a main diaphragm, a movable electrode carried by said diaphragm, a suitable support, a stationary electrode mounted upon said support, comminuted material between the opposing surfaces of said electrodes, and a box inclosing said electrodes and comminuted material, said box having flat front and back walls of thin, flexible and springy material adapted to serve as medium of resilient connection between said diaphragm and support. 105

21. In a telephone-transmitter, the combination of a main diaphragm, a front electrode-surface adapted to vibrate with the diaphragm, a suitable support, a back electrode-surface adapted to remain stationary with said support, comminuted material interposed between said electrode-surfaces, and means for inclosing said comminuted material including front and back supplemental diaphragms, said supplemental diaphragms consisting of thin flat 110 pieces of springy material adapted to serve as medium of resilient connection between the main diaphragm and said support.

22. In a telephone-transmitter, the combination of a main diaphragm, a vibratory elec-

trode connected with said diaphragm, a stationary electrode opposed to said vibratory electrode, comminuted material interposed between said electrodes, and a box inclosing said electrodes and comminuted material, said box having front and back springy walls, the wall which is associated with the vibratory electrode being adapted to alternately become concave and convex on its outer surface during the vibration of the said diaphragm, and the wall which is associated with the stationary electrode being held against becoming convex on its outer surface.

23. In a telephone-transmitter, the combination of a main diaphragm, front and back supplemental diaphragms of yielding and springy material, front and back electrode-surfaces carried by said front and back supplemental diaphragms respectively, comminuted material interposed between said electrode-surfaces, suitable connection between the main diaphragm and the front electrode-surface and supplemental diaphragm, a bridge, and adjustable connection between the said bridge and the said back electrode-surface and supplemental diaphragm, the center of said back supplemental diaphragm being held stationary by said adjustable connection, whereby said bridge and supplemental diaphragms 30 yieldingly oppose the vibrations of the main diaphragm in both directions.

24. In a telephone-transmitter, the combination of a metallic sleeve, a metallic box or inclosure, a vibratory front electrode, a mass of granular carbon, a stationary back electrode, and a metallic stem, all connected up in series in the order mentioned, the said sleeve inclosing the said stem, a diaphragm connected to vibrate said front electrode, and 40 a bridge supporting the said sleeve and stem and holding the back electrode against movement.

25. In a telephone-transmitter, the combination of a metallic sleeve, a metal box with a flexible back wall, a vibratory front electrode, a mass of granular material, a stationary back electrode, and a metallic stem, all connected up in series in the order mentioned, the said sleeve inclosing the said stem, a diaphragm 50 connected to vibrate said front electrode, such vibrations being yieldingly opposed by said flexible wall, and a bridge supporting the sleeve and stem and holding the back electrode against movement.

55. 26. In a telephone-transmitter, the combination of a metallic sleeve, a metallic box composed of front and back walls having their perimeters or peripheral portions tightly fastened together, a vibratory front electrode, a mass of granular material, a stationary back electrode, and a metallic stem, all connected up in series in the order mentioned, the said sleeve inclosing the said stem, a diaphragm connected to vibrate said front electrode, and 60 a bridge adjustably supporting said sleeve and

thereby normally holding said back electrode against movement.

27. In a telephone-transmitter, the combination of a vibratory front electrode, a stationary back electrode, granular carbon interposed between said electrodes, a diaphragm for vibrating the said front electrode, and a bodily-vibratory box inclosing said electrodes and granular carbon, said box having thin flat resilient front and back walls, whereby the 75 bodily vibrations of said box are of less amplitude than the vibrations of said front electrode.

28. In a telephone-transmitter, the combination of a metallic sleeve, a metallic auxiliary diaphragm, a vibratory front electrode, a mass of granular carbon, a stationary back electrode, and a metallic stem, all connected up in series in the order mentioned, the said sleeve inclosing the said stem, a diaphragm 85 for vibrating the front electrode, and a metallic member adjustably supporting the said sleeve and thereby normally holding said back electrode against movement.

29. A telephone-transmitter, comprising 90 front and back electrode-surfaces, granular carbon interposed in suitable quantity directly between said surfaces, a main diaphragm connected with the front electrode-surface, a suitable vibration-opposing member connected 95 with the rear electrode-surface, the granular carbon being inclosed by a box having thin and perfectly-flat resilient front and back walls connected respectively with said diaphragm and member, and said box having also an annular non-yielding wall or peripheral portion connecting said resilient front and back walls, whereby said flat front and back walls constitute medium of resilient connection between said diaphragm and member, and whereby 100 said carbon is subjected to variable pressure by said electrode-surfaces together with a casting rigidly connected with said member, whereby the center of said resilient back wall is held stationary. 110

30. A telephone-transmitter comprising a back electrode, a stem on said electrode, a metal plate through which the stem extends, insulation between the said plate and electrode, a sleeve mounted on and insulated from the said 115 stem, a nut on said stem, and insulation between the nut and sleeve, whereby the plate, insulation and sleeve are clamped tightly between the nut and electrode.

31. A telephone-transmitter comprising a 120 back electrode provided with a threaded stem, a metal cup through which the stem extends, said cup inclosing the electrode, insulation between the cup and electrode, a metal sleeve mounted on said stem and insulated therefrom, 125 one end of said sleeve engaging the central portion of said cup, a couple of nuts on the threaded end of said stem, and insulation encircling the stem and interposed between the said nuts and the end of the sleeve, whereby the cup, 130

insulation and sleeve are clamped tightly between the electrode and one of said nuts.

32. A telephone-transmitter comprising a disk having its face acting as an electrode and its back provided with a threaded stem, a metal cup inclosing the electrode and through which the said stem extends, a nut on the end of said stem, a sleeve mounted on the stem and insulated therefrom, said sleeve being clamped endwise between the cup and nut, and suitable insulation between the electrode and cup.

33. A telephone-transmitter comprising two thin and perfectly smooth resilient auxiliary diaphragms carrying front and back electrode-surfaces with granular carbon interposed in suitable quantity directly between said surfaces, means for holding the center of one of said diaphragms stationary, together with main diaphragm means adapted to receive the voice vibration and connected to alternately compress the centers of said auxiliary diaphragms toward each other and draw the same apart, and to thereby produce the relative movement between the two opposed electrodes.

34. A telephone-transmitter comprising a box composed of a rigid ring closed at each side by a thin resilient auxiliary diaphragm, oppositely-arranged electrodes secured to middle portions of said thin resilient auxiliary diaphragms, granular carbon interposed between said electrodes, a casing rigidly connected with one of said electrodes, together with main diaphragm means adapted to receive the voice vibration and connected to alternately compress the centers of said auxiliary diaphragms toward each other and draw the same apart, and to thereby produce the relative movement between the two opposed electrodes.

35. A telephone-transmitter comprising a casing, a pair of oppositely-arranged elec-

trodes, granular carbon between said electrodes, means for inclosing the electrodes and granular carbon consisting of two thin resilient auxiliary diaphragms rigidly separated at their margins, and as to the three elements, to wit, one electrode, another electrode, and the means for rigidly separating the two resilient auxiliary diaphragms, at least one of such elements being stationary and rigidly connected with the said casing, together with main diaphragm means adapted to receive the voice vibration and connected to alternately compress the centers of said auxiliary diaphragms toward each other and draw the same apart, and to thereby produce the relative movement between the two opposed electrodes.

36. A telephone-transmitter comprising a casing, a pair of oppositely-arranged electrodes, granular carbon between said electrodes, means for inclosing the electrodes and granular carbon consisting of two thin resilient auxiliary diaphragms rigidly separated at their margins, and as to the three elements, to wit, one electrode, another electrode, and the means for rigidly separating the two resilient walls, at least one of said elements being stationary and rigidly connected with the said casing, together with main diaphragm means adapted to receive the voice vibration and connected to alternately compress the centers of said auxiliary diaphragms toward each other and draw the same apart, and to thereby produce the relative movement between the two opposed electrodes.

Signed by me at Chicago, Cook county, Illinois, this 10th day of August, 1901.

HENRY P. CLAUSEN.
